UNITED STATES PATENT OFFICE.

WILLIAM LINDENMAYER, OF NEW YORK, N. Y.

TOILET CASE.

Application filed June 9, 1923. Serial No. 644,388.

To all whom it may concern:

Be it known that I, WILLIAM LINDENMAYER, a citizen of the United States, residing at New York city, in the county of New York and State of New York, have invented certain new and useful Improvements in Toilet Cases, of which the following is a specification.

My invention relates to toilet cases, of the type ordinarily known as "vanity cases", and has particular reference to improvements in the toilet case shown in my Patent No. 1,456,454, granted under date of May 22nd, 1923.

An important object of the invention is to combine in or with a toilet case, a coin holding receptacle, in a manner whereby the coin holding receptacle will be secure, to a considerable extent, against detection.

A further object of the invention is to provide a novel arrangement of mirror with the powder and rouge compact holding receptacles.

Other objects and advantages of the invention will be apparent during the course of the description.

In the accompanying drawings forming a part of this specification, and in which like numerals are employed to designate like parts throughout the same,

Figure 1 is a perspective view of a toilet case embodying my invention,

Figure 2 is a side elevation of the same, parts being shown in central longitudinal section,

Figure 3 is a side elevation of a toilet case embodying a modification of my invention.

Figure 4 is a side elevation of the same, showing the coin receptacle open, and,

Figure 5 is a plan view, of toilet cases of different shapes embodying either form of the invention.

In the drawings, wherein for the purpose of illustration are shown preferred embodiments of my invention, attention being called first to Figures 1 to 5 inclusive; the numeral 10 designates a tubular body portion, serving as a chamber or compartment

for receiving and holding a relatively long powder compact, 11. This body portion is shown as cylindrical, for the purpose of illustration, or may be made in any desired shape, such as square, or approximately elliptical, as indicated in Figure 5. The tubular body portion 10 is provided with a

closed bottom 12, while its top is open. The powder compact 11 rests upon a feed spider 13, having resilient arms 14, the ends of which are preferably bent downwardly into angular portions 15, which frictionally engage the inner wall of the tubular body portion. This spider is shown in detail in Figure 5 of my Patent No. 1,456,454, above referred to. The feed spider 13 is provided with a radial arm 16, preferably rigid, projecting through a longitudinal slot 17, and carrying a button 18. By forcing the button 18 upwardly, the powder compact 17 will be elevated. The angular portions 15 are adapted to more readily slide upwardly upon the inner wall of the tubular body portion 10 than downwardly, and hence the powder compact may be advanced upwardly, but will not move downwardly, unless subjected to excessive pressure. The usual powder puff may be carried within the tubular body portion 10, upon the upper end of the powder compact.

The numeral 19 designates a rouge compartment or receptacle, which is shown as cylindrical to conform to the shape of the tubular body portion 10, and may be made in any desired shape, corresponding to the selected shape of the tubular body portion. This rouge compartment or receptacle is preferably of the same diameter as the tubular body portion 10. The compartment or receptacle 19 has its upper end closed by a top 20, while its lower end is open. The lower open end of the receptacle is adapted to engage with the upper open end of the tubular body portion 10 and is hinged thereto, as clearly indicated at 21. The receptacle 19 is preferably provided with a resilient catch 22, for detachable locking engagement with a stud 23, formed upon the upper end of the tubular body portion. Any other suitable means may be employed to hold the receptacle 19 in the closed position. The foregoing description is common to all forms of the invention.

In Figures 1 and 2, the numeral 24 designates a mirror or reflecting element, which is pivotally connected with receptacle 19, by means of a hinge 25. This hinge is preferably located slightly within the receptacle, at the lower open end thereof, whereby the mirror is adapted to be folded into the lower open end of the receptacle, as clearly illustrated in Figure 2. This mirror 24 has one side only serving as a reflecting sur-

face, and this reflecting side is arranged uppermost, in the closed position, Figure 2. The receptacle 19 receives the rouge compact 26, and the usual puff, in its upper closed end, as shown.

Arranged at the opposite or lower end of the tubular body portion 10 is a coin receptacle 27, corresponding in shape and size to the tubular body portion 10, and somewhat resembling the rouge receptacle 19. The coin receptacle 27 is hinged to the lower closed end of the tubular body portion 10, at 28, and the lower end 29 of this receptacle is closed, while its upper end is open, as shown. The coin receptacle 27 carries a resilient catch or latch 30, for engaging with a suitable stud, similar to the stud 23, formed upon the lower end of the tubular body portion 10, to lock the coin receptacle 20 in the closed position. Any other suitable means may be employed for this purpose. The coin supporting or engaging means within the receptacle 27 will be described hereinafter.

Reference is now had to Figures 3 and 4 of the drawings, wherein is shown a modification of the invention, the same rouge holding receptacle 19 is employed, and a mirror 31 is hinged within the lower open end of the receptacle 19, at 32. The hinge 32 is remote from the hinge 21. The mirror 31 is provided upon its opposite sides with reflecting surfaces, instead of having only one reflecting surface, as shown in Figure 1. The advantage of this double mirror is that it may be used in connection with the powder compact, by opening the receptacle 19, but without swinging the mirror to the raised position.

The same coin receptacle 27 is employed, which is hinged to the lower end of the tubular body portion 10, as described in connection with the first form of the invention. Within each coin receptacle is a follower 33, moved upwardly by a compressible coil spring 34. The coins are supported upon the follower 33, and are held against accidental displacement by inwardly projecting lugs or teeth 35, arranged at one side of the center of the receptacle. By this means, the edge of the coin may be depressed, and the coin will become angularly displaced, as shown in Figure 4, and hence may be readily removed. A particular advantage of this construction is that the usual coin slot found in the ordinary coin holding receptacle is omitted, and when the coin receptacle is in the closed position, its identity as such, is protected, to a considerable extent.

In the form of the invention shown in Figures 3 and 4, the numeral 36 designates a lip stick receptacle, having its bottom closed and its upper end open, which upper end is hinged to the lower closed end of the coin receptacle 27, at 37. A latch 38 is secured to the receptacle 36 and is adapted for detachable engagement with the receptacle 27, as described in connection with the latch 30.

It is obvious that it would be highly convenient to provide a coin holder associated with a toilet case, and by virtue of the peculiar arrangement and construction of the elements which I employ, this is accomplished, and at the same time the presence of the coin holder, as such, is concealed, to a considerable extent. As a matter of fact, it is not probable that the coin holder would be detected. It is thus seen that the elements of the toilet case are employed as a means for shielding the presence of the coin holder.

In the use of the device, as shown in Figure 1, the receptacle 19 may be moved to the open position, and the powder and rouge applied, with the aid of the mirror 24. The same is true of the device shown in Figures 3 and 4. When it is desired to use a coin, the coin receptacle may be opened, as clearly shown in Figure 4, without disturbing the contents of the rouge and powder receptacles, or the lip stick receptacle.

It is to be understood that the forms of my invention herewith shown and described, are to be taken as preferred examples of the same, and that various changes in the shape, size, and arrangement of parts may be resorted to without departing from the spirit of my invention, or the scope of the subjoined claim.

Having thus described my invention, what I claim is:

A coin holding receptacle, a cover member hinged to the receptacle and having a catch element, a resilient latch secured to the coin holding receptacle substantially diametrically opposite the hinge and projecting above the receptacle to engage with the catch element, inwardly projecting lug means secured to the receptacle upon the opposite side of the center of the receptacle from the resilient catch, and yielding means to normally hold the coin in engagement with the lug means, said resilient catch serving as an obstruction element for the coin whereby the coin must be properly tilted before it can be removed.

In testimony whereof I affix my signature.

WILLIAM LINDENMAYER.
